UNITED STATES PATENT OFFICE.

JOSEPH E. COCHRAN, OF ELKHART, INDIANA.

MEASURING-MACHINE.

1,086,647.

Specification of Letters Patent.

Patented Feb. 10, 1914.

Application filed August 17, 1911. Serial No. 644,547.

To all whom it may concern:

Be it known that I, JOSEPH E. COCHRAN, a citizen of the United States, residing at Elkhart, in the county of Elkhart and State 5 of Indiana, have invented certain new and useful Improvements in Measuring-Machines, of which the following is a specification.

This invention relates to improvements in 10 measuring machines particularly adapted, though not necessarily limited in its use, to measuring commodities for packaging purposes and one of the objects of the invention is to provide an improved machine of this 15 class which will be of simple and durable construction and which will be positive and accurate in operation.

A further object is to provide an improved machine of this class having means whereby 20 it may be readily adjusted to vary the quantities of the commodity delivered therefrom.

A further object is to provide an improved machine of this class having friction driving mechanism and means whereby the parts 25 of the driving mechanism may be readily adjusted to vary the speed of the machine.

To the attainment of these ends and the accomplishment of other new and useful objects, as will appear, the invention consists 30 in the features of novelty in substantially the construction, combination and arrangement of the several parts hereinafter more fully described and claimed and shown in the accompanying drawings exemplifying 35 the invention, and in which—

Figure 1 is a top plan view of an improved machine of this class constructed in accordance with the principles of this invention. Fig. 2 is an enlarged detail sectional view taken on line 2—2, Fig. 5. Fig. 40 3 is a detail sectional view taken on line 3—3, Fig. 4. Fig. 4 is a top plan view of one of the gates or cut-offs for cutting off the supply of the commodity. Fig. 5 is a 45 sectional view taken on line 5—5, Fig. 1. Fig. 6 is a detail sectional view of a portion of the telescoping members constituting a portion of the discharge outlet of the hopper. Fig. 7 is a sectional view on line 7—7, 50 Fig. 1. Fig. 8 is a sectional view on line 8—8, Fig. 5. Fig. 9 is an enlarged detail view partly in elevation and partly in section, showing a portion of the mechanism

for varying the amount of the commodity delivered from the machine. Fig. 10 is a 55 side elevation of the machine taken from the right hand side of Fig. 1. Fig. 11 is a detail sectional view on line 11—11, Fig. 8.

Referring more particularly to the drawings and in the present exemplification of 60 the invention the numeral 10 designates four uprights or posts upon which the mechanism is supported and these uprights are mounted upon a suitable base 11. The uprights are provided throughout a greater portion of 65 their length, preferably the upper portions, with screw threads 12 for a purpose to be hereinafter set forth. Supported by the uprights, preferably by their upper ends, are spaced members 13, 14, preferably in the 70 form of disks or plates (see particularly Figs. 5 and 7) between which a rotating disk 15 is disposed and these members 13, 14, serve as a housing for the disk. The members 13, 14, may be of any desired configuration 75 but are preferably circular as shown, and passing through the center of the plates is an upright shaft 16 to which the hub 17 of the disk 15 is connected, preferably by means of a fastening device 18 and the shaft 80 16 is provided with a groove or way 19 for a purpose to be set forth. Secured to the shaft 16 is a worm wheel 20 which is located preferably above the member 14 and a worm gear 21 (see also Fig. 1) meshes with the 85 worm gear 20. This worm gear 21 is connected to a shaft 22 which latter is journaled in suitable bearings 23 supported by any fixed portion of the mechanism preferably by the member 14 so that the shaft 90 22 will be disposed at right angles to the shaft 16. A motor 24 having a shaft 25, is supported by a suitable bracket 26 so that the shaft 25 will be disposed in proximity to the shaft 22 and preferably at right angles thereto. A friction driving gear 27 is secured to the shaft 25 to rotate therewith and co-operates with a friction disk 28 secured to the shaft 22. In order to hold the disk 28 against the driving gear 27, an elastic member 29 in the form of a coil spring is provided which surrounds the shaft 22 with one end of the spring engaging a collar or shoulder 30 on the shaft 22 and the other end bearing against one of the bearings 23 of 100 the shaft 22 so that when the shaft 25 is ro-

105

tated, the motion thereof will be transmitted through the medium of the friction gearing 27, 28, to the shaft 22 which in turn will rotate the worm gear 21 and the latter will rotate the worm gear 20 as well as the shaft 16. Inasmuch as the disk 15 is secured to the shaft 16 it will be manifest that when the latter is rotated the disk will be correspondingly rotated. This disk 15 is provided with an aperture or opening 32 therethrough, as shown more clearly in Fig. 4, and one edge of the opening is beveled or inclined as at 33 for a purpose to be set forth.

In order to vary the speed of rotation of the shaft 22 and consequently the disk 15, the casing of the motor 24 is provided with a bearing 34 into which the extremity 35 of the shaft 25 projects. An adjusting screw 36 is threaded into this bearing 34 and is provided with a contact portion 37 adapted to engage the extremity 35 of the shaft 25 so that when the screw 36 is adjusted in one direction, the shaft 25 will be moved longitudinally to move the friction gear 27 toward the axis of the disk 28 and against the tension of an elastic member 38, which latter surrounds a portion of the shaft 35, with one extremity having engagement with a bearing 39 in which the shaft 25 is journaled, and the other extremity of the elastic member has engagement with the sleeve or collar 40 which is adjustably mounted on the shaft 25. When the screw 36 is adjusted in the opposite direction the elastic member 38 will tend to move the friction gear 27 toward the periphery of the disk 28. In order to permit the shaft 22 to be moved longitudinally in its bearings 23 and without disconnecting the worm gear 21 with respect to the gear 20, the worm gear 21 is connected to the shaft 22 by means of a feather connection comprising grooves in the shaft and in the worm gear and a key 41 (see Fig. 2) which enters the grooves. The member 13 is provided with an aperture or opening therethrough with which the opening 32 in the disk 15 is adapted to register, and a hopper 42 having a reduced outlet portion 43 is supported in any suitable manner so that the outlet will register with the opening in the member 13.

A tubular member 44 (see particularly Fig. 6) is supported by the member 14 below the opening in the member 13 and in such position as to register with the opening in the member 13 when the disk 15 is moved so that the opening 32 will register with the opening in the member 13. This tubular member 44 may be of any desired length and a supporting member 45 is provided with an opening through which the tubular member 44 projects and a tubular member 46 is supported by the member 45 to surround the opening therein and with which 65 tubular member 46 the tubular member 44

telescopes. This member 45 is supported by means of the uprights 10 and is provided with hangers 47 within which are arranged gears 48, one for each of the uprights 10. These gears 48 are preferably in the form of nuts or collars having internal screw threads which coöperate with the threaded portions 12 on the respective uprights 10. The peripheries of these gears 48 are provided preferably with worm threads with which worm gears 49 mesh. One of these gears 48 is provided for each of the uprights 10 and one of the gears 49 is provided for each of the gears 48. Shafts 50, which are journaled in suitable bearings—preferably the hangers—are provided and these shafts connect the gears 49 in pairs. A shaft 51 (see Fig. 7) is journaled in suitable bearings carried by the member 45 and is arranged transversely of the shafts 50. Carried by this shaft 51 are worm gears 52 which mesh with worm gears 53 on the respective shafts 50. An operating handle 54 (see particularly Figs. 1 and 7) is connected with one end of the shaft 51 for rotating the latter. A pair of members 55, 56, similar to the members 13, 14, are supported by the uprights 10 below the member 45 and one of these members, preferably the member 55, is provided with hangers 57 in which are journaled gears 58 similar to the gears 48. These gears 58 are provided with internal threads (see also Fig. 9) which coöperate with the threads 12 on the uprights 10 and are also provided with peripheral worm threads. A worm gear 59 meshes with the worm threads on the periphery of each of the gears 58 and shafts 60 are provided which connect the gears 59 in pairs similar to the gears 49. Each of the shafts 60 is provided with a worm gear 61, and worm gears 62 on a transverse shaft 63 mesh with the respective worm gears 61. This shaft 63 is journaled in suitable bearings carried by the member 55.

The shaft 51 is arranged above the shaft 63, and motion is imparted to the latter shaft from the shaft 51 through the medium of a gear 64 (see Figs. 1 and 7) on the shaft 51, which meshes with a gear 65 (see also Fig. 9) on an upright shaft 66 and this shaft 66 has a sliding connection with a gear 67 which latter meshes with a gear 68 carried by the shaft 63. It will thus be manifest that when the crank 54 is rotated to rotate the shaft 51, the shaft 63 will also be rotated and as these two shafts 51, 63, are rotated the respective gears 48, 58, will be rotated upon the uprights 10 and will be moved up and down said uprights, according to the direction of rotation of the handle 54 to cause the members 45 and 55, 56, to travel toward or away from the members 13, 14. The members 55, 56, are spaced from each other similar to the members 13, 14, and as

shown in Fig. 7, and the shaft 16 passes through these members 55, 56. A disk 69 similar to the disk 15 is provided with an aperture 70 (see Fig. 1) similar to the aperture 32 in the disk 15 and this aperture 70 is provided with a beveled or inclined edge 71 similar to the inclined edge 33. The disk 69 is connected with the shaft 16 for rotation therewith and for adjustment longitudinally with respect to the shaft, such as by means of a key which travels in the groove 19 in the shaft 16, so that when the members 55, 56, are adjusted or moved upon the uprights 10 in the manner above set forth, the disk 69 will be correspondingly moved so as to move the disk toward or away from the disk 15 to vary the distance between the disks.

The members 55, 56, are provided with openings therethrough which register and these registering openings are adapted to register with the openings in the members 13, 14. A tubular member 72 is supported by the member 56 and surrounding the opening therethrough and the tubular member 72 is of such a size and configuration that it will receive the tubular member 46 as shown more clearly in Fig. 6 so that when the members 55, 56, and 45, are moved toward the top of the uprights 10, the tubular members 72, 46, 44, will telescope with each other as shown in Fig. 6, and, together with the tubular member 43, will form a chambered outlet for the hopper. The gears 58, 59 and 48, 49, are so proportioned with respect to each other that the gears 58 will rotate approximately twice as fast as the gears 48 so that when the parts are adjusted from the position shown in Fig. 10 by the operation of the handle 54, the members 55, 56, will travel twice as fast as the member 45 so that by the time the member 45 reaches the member 13, the members 55, 56, will move into the position shown in Fig. 6. A discharge spout 73 is supported by the member 55 to receive the material discharged through the members 55, 56, and this spout 73 may be of any desired configuration but preferably of a configuration to adapt it to be inserted into a bag or other receptacle. The hopper 42 is preferably arranged to one side of the shaft 16 and on the side opposite to that on which the motor 24 is attached.

In use the disk 69 is first adjusted with respect to the disk 15 so that the space within the tubular telescoping members 44, 46, 72, will hold the exact amount of the commodity to be placed within the package. Having once been thus adjusted, the motor 24 is then started. This will rotate the shaft 16 as well as the disks 15, 69. As soon as the disk 69 reaches a position that its opening 70 will register with the telescoping tubular members, the commodity in the space between the disks 15, 69, within the tubular

members, will be released so as to be discharged through the outlet 73 and into the receptacle. By the time this quantity of the material has been thus discharged a solid portion of the disk 69 will extend across the tubular members to form a closure therefor and thereby shut off the discharge of the material. At the same time the disk 15 will assume a position that the opening 32 therein will be adjacent the hopper to permit another supply of the commodity or material to be deposited upon the disk 69. A further rotation of the disk 15 will shut off the supply of the material until that amount which is contained between the disks and within the telescoping tubular members has been discharged. The disks rotate in the direction indicated by the arrow in Fig. 4, that is, in a direction so as to cause the beveled edges 33 and 71 to be presented to the material so as to cut off the supply and thereby avoid damage to the material.

When it is desired to vary the speed of rotation of the disks all that is necessary is to adjust the screw 36 to shift the motor shaft 90 longitudinally and thereby vary the position of the friction driving gear 27 with respect to the friction disk 28 by moving the driving gear 27 toward or away from the periphery of the disk 28.

What is claimed as new is—

1. In a machine of the class described, the combination of a hopper having a chambered discharge outlet, spaced rotatable cut-off members operable transversely of said outlet for controlling the outlet, means for operating said members to cause the members to alternately open and close the outlet at different points, and means for relatively adjusting said members to vary the capacity of said chambered outlet.

2. In a machine, of the class described, the combination of a hopper having a chambered discharge outlet, spaced rotatable cut-off members arranged to control said outlet and having their axis of rotation disposed outside of the outlet, means for rotating said members to cause them to operate alternately to open and close the outlet, and spacing mechanism for relatively spacing said members to vary the measuring capacity of said chambered outlet.

3. In a machine of the class described, the combination of a hopper having a chambered discharge outlet, spaced rotatable disks arranged to operate across the outlet, the axis of rotation of said disks being disposed outside of the outlet, said disks being each provided with an opening therethrough adapted to register with the outlet, and power mechanism for rotating the disks to cause the openings to be alternately moved into and out of register with the outlet.

4. In a machine of the class described, the combination of a hopper having a chambered

discharge outlet, spaced rotatable disks arranged to operate across the outlet, the axis of rotation of said disks being disposed outside of the outlet, said disks being each provided with an offset opening therethrough adapted to register with the outlet, means for rotating the disks to cause the openings to be alternately moved into and out of register with the outlet, and means for relatively adjusting the disks to vary the space therebetween.

5. In a machine of the class described, the combination of a hopper having a chambered discharge outlet, spaced rotatable disks arranged to continuously operate across the outlet and each being provided with an opening therethrough adapted to be brought into register with the outlet, a common shaft to which the disks are secured, said shaft being disposed outside of the outlet and said disks being secured thereto with the openings therein out of register, and means for driving the shaft to cause the openings in the disks to be moved 20 across the outlet, one of the disks operating to open the outlet when the other disk operates to close the outlet.

6. In a machine of the class described, the combination of a hopper having a chamber forming outlet, rotatable disks arranged to operate across the outlet at different levels and each being provided with an opening therethrough adapted to be brought into register with the outlet, a shaft to which the disks are secured, said shaft being disposed outside of the outlet and said disks being secured thereto with the openings therein relatively offset, means for rotating the shaft to cause the openings in the disks to be moved across the outlet, one of the disks operating to open the outlet when the other disk operates to close the outlet, and means for relatively adjusting the disks longitudinally of the shaft to vary the space between the disks.

7. In a machine of the class described, the combination of a hopper having a variable capacity chamber embodying adjustable telescoping tubular members, spaced cut-off members operable in planes transverse to said tubular members, and adjustable with the tubular members and relatively one with respect to the other, actuating mechanism common to the cut-off members for causing them to alternately open and close said chamber, and means for relatively adjusting the cut-off members and the said telescoping members simultaneously.

8. In a machine of the class described, the combination of a hopper having a variable capacity chamber embodying adjustable telescoping tubular members, spaced cut-off members operable in parallel planes transverse to the axis of said tubular members, and adjustable with the tubular members

and relatively one with respect to the other, actuating mechanism common to the cut-off members for causing them to alternately open and close said chamber, and means for adjusting the telescoping members and for causing one of them to move at a greater rate of speed than the other member and for relatively adjusting the said cut-off members to vary the space between the cut-off members within the tubular members.

9. In a machine of the class described, the combination of a hopper having a variable capacity receptacle embodying adjustable telescoping tubular members, spaced cut-off members adjustable with the tubular members and relatively with respect to each other, said cut-off members operating across the tubular members, a shaft common to and connected with the cut-off members for causing one of said members to close the receptacle when the other member opens the receptacle, and with respect to which shaft one of the cut-off members is longitudinally adjustable, and common mechanism for relatively adjusting the cut-off members and for also adjusting the tubular members.

10. In a machine of the class described, the combination of a hopper having a discharge chamber embodying adjustable telescoping tubular members, spaced cut-off members adjustable with the tubular members and relatively with respect to each other, said cut-off members operating across the tubular members, a shaft common to and connected with the cut-off members for causing them to control the passage of material through said chamber and with respect to which shaft one of the cut-off members is longitudinally adjustable, and means for adjusting one of the said tubular members at a greater rate of speed than the other tubular member and for relatively adjusting the said cut-off members to vary the space between the latter.

11. In a machine of the class described, the combination of a hopper having a measuring receptacle, a support for the hopper, embodying uprights, traveling members mounted to move upon the uprights, tubular members supported by the first said members and telescoping with each other, said tubular members forming the measuring receptacle, spaced cut-off members relatively adjustable to vary the space therebetween and operating across the tubular members to alternately control the passage of material through said measuring receptacle, means for thus operating the cut-off members, and means for relatively adjusting the said traveling members and also the cut-off members.

12. In a machine of the class described, the combination of a hopper having a measuring chamber, a support for the hopper embodying uprights, traveling members mount-

ed to move upon the uprights, tubular members supported by the first said members and telescoping with each other, said tubular members forming the measuring chamber, spaced cut-off members relatively adjustable to vary the space therebetween and operating across the tubular members to alternately open and close the entrance and exit of said chamber, means for thus operating the cut-off members, and means for relatively adjusting the said traveling members to cause one of the said members to travel at a greater rate of speed than the other and for also relatively adjusting the said cut-off members.

13. In a machine of the class described, the combination of a hopper having a measuring chamber, a support for the hopper embodying uprights, traveling members mounted to move upon the uprights, tubular members supported by the first said members and telescoping with each other, said tubular members forming the measuring chamber, spaced cut-off members relatively adjustable to vary the space therebetween and operating across the tubular members to control the passage of material through the tubular members, means for thus operating the cut-off members, and interengaging means between the traveling members and the uprights for relatively adjusting the said members.

14. In a machine of the class described, the combination of a hopper having an outlet, a support for the hopper embodying uprights, spaced traveling members, means embodying gearing connecting the traveling members with the uprights, tubular members supported by the said members, telescoping with each other and registering with the outlet of the hopper, cut-off members spaced apart and arranged to operate across the telescoping members, said cut-off members being relatively adjustable to vary the space therebetween, means for imparting motion to said cut-off members, and means for operating the said gearing for adjusting the parts.

15. In a machine of the class described, the combination of a hopper having an outlet, a support for the hopper embodying uprights, spaced traveling members, means embodying gearing connecting the traveling members with the uprights, tubular members supported by the said members, telescoping with each other and registering with the outlet of the hopper, cut-off members spaced apart and arranged to operate across the telescoping members, said cut-off members being relatively adjustable to vary the space therebetween, means for imparting motion to said cut-off members, and means for operating the said gearing for adjusting the parts, the said gearing of one of the members being so proportioned with relation to

the gearing of the other member that one of the members will travel at a greater rate of speed than the other members.

16. In a machine of the class described, the combination of a hopper having an outlet, a support for the hopper embodying uprights, spaced traveling members, means embodying gearing connecting the traveling members with the uprights, tubular members supported by the said members, telescoping with each other and registering with the outlet of the hopper, cut-off members spaced apart and arranged to operate across the telescoping members, said cut-off members being relatively adjustable to vary the space therebetween, means for imparting motion to said cut-off members, and means common to all of the said gearing for operating the same.

17. In a machine of the class described, the combination of a hopper having an outlet, supports therefor, spaced traveling members, operating gearing connecting the respective members with the support, means common to all of the gearing for operating the latter and embodying a crank, telescoping tubular members carried by the traveling members and registering with the outlet of the hopper, rotatable cut off disks spaced from each other and disposed across the tubular members and having openings therethrough adapted to be brought into and out of register with the tubular members in timed relation, a portion of the edge of each opening being beveled, and means for rotating the disks.

18. In a machine of the class described, the combination of a hopper having an outlet, supports therefor, spaced traveling members, operating gearing connecting the respective members with the supports, means common to all of the gearing for operating the latter and embodying a crank, telescoping tubular members carried by the traveling members and registering with the outlet of the hopper, spaced rotatable cut-off disks adjustable with said traveling members to vary the space between said disks, said disks being disposed across the tubular members and having openings therethrough adapted to be brought into and out of register with the tubular members, a portion of the edge of each opening being beveled, and means for rotating the disks.

19. In a machine of the class described, the combination of a hopper having an outlet, supports therefor, spaced traveling members, operating gearing connecting the respective members with the supports, means common to all of the gearing for operating the latter and embodying a crank, tubular members carried by the traveling members to telescope with each other and to register with the outlet of the hopper, spaced rotatable cut-off disks adjustable with said

traveling members to vary the space between them, said disks being disposed across the tubular members and each having an opening therethrough adapted to be brought into and out of register with the tubular members, a portion of the edge of each opening being beveled, a shaft connecting the disks for simultaneous rotation and with respect to which shaft one of the disks is longitudinally adjustable, and means for rotating the shaft.

20. In a machine of the class described, the combination of a hopper having an outlet, supports therefor, spaced traveling members, operating gearing connecting the respective members with the supports, means common to all of the gearing for operating the latter and embodying a crank, tubular members carried by the traveling members to telescope with each other and to register with the outlet of the hopper, rotatable cut-off disks adjustable with said traveling members to vary the space between them, said disks being disposed across the tubular members and each having an opening therethrough adapted to be brought into and out of register with the tubular members, a portion of the edge of each opening being beveled, a shaft connecting the disks for simultaneous rotation and with respect to which shaft one of the disks is longitudinally adjustable, means for rotating the shaft, and means for varying the speed of rotation of the shaft.

35. In a machine of the class described, the combination of a hopper having an outlet, supports therefor, spaced traveling members, operating gearing connecting the respective members with the supports, means common to all of the gearing for operating the latter and embodying a crank, tubular members carried by the traveling members to telescope with each other and to register with the outlet of the hopper, rotatable cut-off disks spaced from each other to operate across the tubular members and each having an opening therethrough adapted to be brought into and out of register with the tubular members, a portion of the edge of each opening being beveled, a shaft connecting the disks for simultaneous rotation and with respect to which shaft one of the disks is longitudinally adjustable, means for rotating the shaft, and means embodying friction gearing for varying the speed of rotation of the shaft.

60. In a machine of the class described, the combination of a hopper having an outlet, a support therefor, spaced members, gearing for individually connecting the members with the supports and for relatively moving the members on the support, means connecting the gearings for operating the same and for relative adjustment, spaced rotatable cut-off members relatively

adjustable to vary the space therebetween and operating to alternately control the discharge from the hopper, one of said cut-off members being carried by one of the traveling members, means connecting the cut-off members for operation in unison, and mechanism for imparting motion to the last recited means.

70. In a machine of the class described, the combination of a hopper having an outlet, a support therefor, spaced members, gearing for individually connecting the members with the supports and for relatively moving the members on the support, means connecting the gearings for operating the same, spaced rotatable cut-off members relatively adjustable to vary the space therebetween and operating to alternately control the discharge from the hopper, one of said cut-off members being carried by one of the traveling members, means connecting the cut-off members for operation in unison, and mechanism for imparting motion to the last recited means, the said mechanism embodying friction gearing.

75. In a machine of the class described, the combination of a hopper having an outlet, a support therefor, spaced members, gearing for independently connecting the members with the supports and for relatively moving the members on the support, means connecting the gearings for operating the same, spaced rotatable cut-off members, relatively adjustable to vary the space therebetween and operating to alternately control the discharge from the hopper, one of said cut-off members being carried by one of the traveling members, means connecting the cut-off members for operation in unison, and mechanism for imparting motion to the last recited means, the said mechanism embodying friction driving and driven elements and mechanism for adjusting one of the elements with respect to the other to vary the speed of the disk operating means.

90. In a machine of the class described, the combination of a hopper having an outlet, a support therefor, spaced members, gearing for independently connecting the members with the supports and for relatively moving the members on the support, means connecting the gearings for operating the same, spaced rotatable cut-off members relatively adjustable to vary the space therebetween and operating to alternately control the discharge from the hopper, one of said cut-off members being carried by one of the traveling members, means connecting the cut-off members for operation in unison, mechanism for imparting motion to the last recited means, the said mechanism embodying friction driving and driven elements, yielding means for holding the said elements in operative relation and means for relatively adjusting the said ele-

- ments to vary the speed of the disk operating means.
26. In a machine of the class described, the combination of a hopper having an outlet, a support therefor embodying uprights having threaded portions, spaced members movable upon the uprights, nuts engaging the threaded portions of the uprights, and having threaded peripheries, telescoping tubular members supported by the first said members and registering with the outlet of the hopper, driving gears meshing with the threaded peripheries of the respective nuts, means for operating the gears to move the first said members, spaced cut-off members operating across the telescoping members and relatively movable by the adjustment of the first said members, and means for operating the said cut-off members.
27. In a machine of the class described, the combination of a hopper having an outlet, a support therefor embodying uprights having threaded portions, spaced members movable upon the uprights, two sets of nuts engaging the threaded portions of the uprights, and for supporting said movable members, said nuts having threaded peripheries, telescoping tubular members supported by the first said members and registering with the outlet of the hopper, driving gears meshing with the threaded peripheries of the nuts, means connecting the driving gears of the respective series, an adjustable interconnection between the series of gears, for moving the gears to adjust the said members, spaced cut-off members for controlling the outlet of the hopper and relatively adjustable to vary the space therebetween by the adjustment of the said members, and means for operating the said cut-off members.
28. In a machine of the class described, the combination of a hopper having an outlet, a support therefor embodying uprights having threaded portions, spaced members movable upon the uprights, an independent set of rotatable nuts for each member engaging the threaded portions of the uprights, said nuts having threaded peripheries, telescoping tubular members supported by said spaced members and registering with the outlet of the hopper, driving gears meshing with the threaded peripheries of the nuts, means operably inter-connecting the driving gears of the respective series, an adjustable inter-connection between the series of gears for moving the gears to adjust the said members, the operating gears of one of the series being so proportioned with respect to the operating gears of the other series that one of the first said members will move at a greater rate of speed than the other member, spaced cut-off members for controlling the outlet of the hopper and relatively adjustable to vary the space therebetween by the adjustment of the said members, and

means for operating the said cut-off members.

29. In a machine of the class described, the combination of a hopper having a chambered outlet embodying telescoping tubular members, spaced rotatable cut-off members for controlling the outlet, means for adjusting the cut-off members relatively to each other and also the tubular members to vary the capacity of said chambered outlet, means for rotating the cut-off members embodying a friction driving and a friction driven element, means for relatively adjusting the friction elements to vary the speed of the cut-off members, and means for imparting rotation to the driving member.

30. In a machine of the class described, the combination of a hopper having chambered outlet embodying telescoping tubular members, spaced rotatable cut-off members for controlling the outlet, means for adjusting the cut-off members relatively to each other and also the tubular members to vary the capacity of said chambered outlet, means for rotating the cut-off members embodying a friction driving and a friction driven element, a motor, a motor shaft to which the said driving element is connected, and means for longitudinally adjusting the motor shaft to vary the speed of rotation of the friction driven element.

31. In a machine of the class described, the combination of a hopper having a measuring receptacle embodying telescoping tubular members, spaced rotatable cut-off members for controlling the passage of material into and out of said receptacle, means for adjusting the cut-off members relatively to each other and also the tubular members to vary the capacity of said receptacle, means for rotating the cut-off members embodying a friction driving and a friction driven element, a motor, a motor shaft to which the said driving element is connected, and means for longitudinally adjusting the motor shaft to vary the speed of rotation of the friction driven element, the last said means embodying an adjusting screw having an abutment against one end of the motor shaft.

32. In a machine of the class described, the combination of a hopper, telescoping tubular members communicating therewith and forming a measuring chamber spaced rotatable cut-off members for controlling the quantity of material delivered to said measuring chamber, means for adjusting the cut-off members relatively to each other and also the tubular members to vary the capacity of said chamber, means for rotating the cut-off members embodying a friction driving and a friction driven element, a motor, a motor shaft to which the said driving element is connected, means for longitudinally adjusting the motor shaft to vary the speed 130

of rotation of the friction driven element, the last said means embodying an adjusting screw having an abutment against one end of the motor shaft, and yielding means for holding the end of the motor shaft against the screw.

5 In testimony whereof I have signed my

name to this specification, in the presence of two subscribing witnesses, on this 11th day of August A. D. 1911.

JOSEPH E. COCHRAN.

Witnesses:

MARIE SCOTT,

MARGARET DARLING.
